UNITED STATES PATENT OFFICE

2,512,120

VIBRATING APPARATUS

George Harry Strain, Seafood, England

Application October 3, 1944, Serial No. 557,001
In Great Britain December 1, 1943

3 Claims. (Cl. 74—61)

1

The present invention relates to vibrating apparatus for screening, dehydrating or agitating material, the apparatus being of the kind in which the vibratory movements of a primary mass, preferably in the form of an anvil, are imparted to a secondary mass, which carries the material to be treated, by means of an elastic coupling. Machines of this type are marketed under the trade-mark Velosifter registered in the name of the present applicant.

When these machines are in use the two masses are caused alternately to collide and separate, resulting in an unusual motion of the secondary mass.

According to the present invention means are provided whereby collision between the primary and secondary masses can be caused to occur at either end of a stroke or at both ends of a stroke, at the will of the operator, the motion of the secondary mass being suddenly arrested and reversed. The secondary mass, which is in the form of screening compartments or liquid containers, is clamped to a bridge or platform supported between springs which determine the natural frequency of the secondary mass so that it keeps in step with primary mass.

If collision occurs at the upper end of a stroke, material resting on a screen, and tending to lodge in the apertures, is projected upwardly, and the apertures are cleared for the passage of particles when they return to the screen under the action of gravity.

When powdered or broken material is wet and has to be de-watered, the apertures of the screen should be small enough to prevent the passage of material and large enough to allow the liquid to pass through. When the apertures are small, water has a strong tendency to reside in them in the form of globules or films. If collision occurs at the upper end of the stroke, water may be ejected from the apertures in an upward direction together with the material, but on returning to the screen the globules are reformed and the liquid tends to cling to the screen instead of passing through.

If collision occurs at the lower end of the stroke, water is ejected from the apertures, with the assistance of gravity, in a downward direction and it leaves the underside of the screen in the form of spray while the material is retained above the screen. While this is happening certain materials have a tendency to lodge in the apertures and cannot be removed without an ejecting action in an upward direction. If collision is made to occur at both ends of the stroke,

2

the upper collision frees the apertures of lodging material and the lower collision removes the water.

The screening vibrations are rectilinear in character, and if the screens are mounted as shown, the vibrations are perpendicular to the screening surfaces. The screening compartments shown consist of separate sections placed one above the other and clamped firmly together to form chambers enclosed by a lid and bottom for collecting the finest grade of material. A batch of unscreened material is placed in the upper compartment to be segregated according to the underlying screens which may be of any number, the products being removed when the compartments are separated from the machine. This constitutes the batch method of screening. For continuous screening, the compartments would be open at the ends and the surfaces could be inclined by tilting the machine as a whole, or by inclining the screens relatively to the machine, so that material would proceed continuously over the surfaces with the assistance of gravity.

One form of construction of the invention as applied to a vertically operating screening device, is illustrated in the annexed drawings, in which:

Fig. 1 is a side elevation, and
Fig. 2 is a section on the line 2—2 of Fig. 1.
In these drawings, the anvil or primary mass 1 is held and supported by parallel leaf springs 2 secured to a part of the stationary framework 3. The springs 2 guide the anvil so that its motion is substantially rectilinear; they also provide the anvil with a natural frequency which corresponds with the frequency of an unbalanced weight 4 made to rotate about an axle 5 which is secured to the anvil and driven by a belt 6 from a convenient source.

By this arrangement, very little force is needed to vibrate the anvil in the region of its natural frequency and the magnitude of the force is too small to disturb the stationary framework to a noticeable extent.

The secondary mass, comprising screening compartments or containers for liquid or other material, is mounted above the anvil, and guide rods 7 passing freely through holes in the anvil maintain the desired position of the secondary mass relatively to the anvil. The rods 7 are also extended upwards to terminate in screws and wing nuts 8 for clamping the compartments or containers to a bridge piece 9 which is secured to the middle part of the rods. The lower ends

of the rods 1 are screwed and provided with rubber annular discs or pads 10 secured to adjustable supports 11 which are held in the desired position by locknuts 12. The bridge or platform 9 is supported between pairs of coil springs 13. These springs determine the natural frequency of the secondary mass so that it keeps in step with the anvil, and each pair of springs is compressed by a screwed rod 14 passing through the springs and a clearance in either end of the bridge 9. By turning wing-nuts 15 the position of the bridge 9 relatively to the anvil may be adjusted, so that impacts occur where desired in the vibratory cycle.

If collision is to occur at the upper end of the screening stroke, only the rubber pads 10 are adjusted to strike against and separate from the underside of the anvil, alternately, and the intensity of this action may be varied by adjusting wing-nuts 15.

If collision is to occur at the lower end of the screening stroke, stops 16 are brought into action. These stops, provided with rubber pads 17, are screwed into the upper surface of the anvil and secured in the desired position by locknuts 18. The rubber pads 10 are then lowered to prevent them from making contact with the anvil, so that impact only occurs when the underside of bridge 9 strikes against pads 17.

If collision is to occur at both ends of the screening stroke, pads 10 and 17 are all adjusted to be operative, so that two impacts occur in each period of vibration.

It should be mentioned that a vibratory screening action with impacts at both ends of the stroke can be maintained even if the springs 13 are removed from the machine. For this condition very critical adjustment of the stops is essential, and if the load, speed or stop positions vary very slightly, the vibratory action gets out of step and control. With springs 13 in action, both load and speed may be varied over a wide range without the secondary mass getting out of step with the anvil.

With this machine, screening vibrations $\frac{3}{4}$ " in length and 1750 per minute are easily obtained, and as impact occurs in the region of maximum velocity, the ejecting action is very intense and able to keep the apertures of the finest gauze open and clear when screening metal powders. Vibration in the stationary framework is quite unnoticeable and the machine need not be bolted down. The screening gauges are not tensioned; instead they are mounted upon metal frames 19 which lie between the screening sections 20. The frames 19 are spanned with metal rods or bars 21 of suitable stiffness which are spaced to suit the gauze they have to support. The gauze 22 is secured to the frame and bars by soft soldering, so that with this arrangement, screening surfaces are cheaply made and changed.

I claim:

1. Vibrating apparatus of the kind specified comprising a vibrating primary mass, a vibrating secondary mass, spring means between said masses, impact means between said masses, means for adjusting said spring means to cause said secondary mass to assume a vibration frequency in step with that of said primary mass, said secondary mass being mounted above said primary mass, a bridge to which said spring means is applied, and guide rods passing through the two masses and serving to clamp the secondary mass to said bridge.

15 2. Vibrating apparatus of the kind specified comprising a vibrating primary mass, a vibrating secondary mass, spring means between said masses, impact means between said masses, means for adjusting said spring means to cause said secondary mass to assume a vibration frequency in step with that of said primary mass, said secondary mass being mounted above said primary mass, a bridge to which the spring means is applied, guide rods passing through the two masses and serving to clamp the secondary mass to said bridge, elastic pads below the primary mass, and abutment means carried by the lower ends of the guide rods for engaging against said elastic pads.

20 3. Vibrating apparatus of the kind specified comprising a vibrating primary mass, a vibrating secondary mass, spring means between said masses, means for adjusting said spring means to cause said secondary mass to assume a vibration frequency in step with that of said primary mass, guide rods clamped to the secondary mass and passing through the primary mass, and impact means between the masses comprising upper stops secured to the upper portion of the primary mass in position to make contact with the secondary mass at one end of the screening stroke, and lower stops secured to said guide rods and positioned to make contact with the lower surface of the primary mass at the opposite end of the screening stroke.

45 GEORGE HARRY STRAIN.
